UNITED STATES PATENT OFFICE.

JAMES S. REID, OF CLEVELAND, OHIO.

INTERNAL-COMBUSTION ENGINE.

Application filed June 1, 1925, Serial No. 34,098.

This invention relates to improvements in internal combustion engines.

One object of the present invention is to provide an internal combustion engine in which the firing or explosion of the compressed gas is comparatively quick and the firing stroke is comparatively short in extent, and also in which the number of explosions per revolution is reduced to a minimum, thereby reducing to a minimum the amount of heat resulting from the explosions.

Another object is to provide an internal combustion engine in which the power is applied along a main direct line between the explosion chamber and the drive shaft, thereby increasing the power and efficiency of the engine.

A further object is to provide such an engine in which the connecting rod and explosion chamber are formed as a single, unitary, composite structure, the expandable chamber and connecting rod being merged together.

Another object is to produce such an engine which is comparatively light in weight.

More specifically, the present invention comprises a single gas chamber which is adapted to distend as it receives the gas and to be then collapsed for placing the gas under compression for the explosion which in turn again distends the gas chamber from which the exploded gases are then exhausted by collapsing of the gas chamber. In the present form of invention as here defined and illustrated, only a single gas chamber is employed and accordingly there is required but a single spark plug. Each explosion of compressed gas is, according to the present form of invention, sufficient to drive the flywheel through a complete revolution because of the increased efficiency in power produced by each explosion, this being due to the construction and arrangement of the several parts. With such increased efficiency, it is possible to reduce the period of explosion to a minimum and in fact in the present form of invention the firing stroke extends over only approximately 90° or one quarter of a revolution of the flywheel. Thus the firing of the gas is comparatively quick and the number of explosions is comparatively small, with the result that the amount of heat developed in the operation of the engine is likewise reduced to a minimum with a corresponding increase in efficiency.

Referring to the figures of the drawing,

Fig. 1 is a sectional view taken on line 1—1, Fig. 2; and Fig. 2 is a sectional view taken on line 2—2 of Fig. 1, these two figures being taken at 90° to each other.

The driven shaft 1 is mounted in the frame or casing 2 and is provided with composite fly wheels, each of which is formed of two parts so as to permit adjustment for taking up wear, as will be later explained. 60 Each flywheel for instance comprises an outer part 3^a and an inner part 3^b with adjusting screws 4 which extend through the outer parts 3^a and engage in correspondingly formed depressions in the contacting faces 65 of the parts 3^b so as to force the same inwardly whenever it might become necessary to take up wear on the inside faces of the inner parts 3^b. The occasion for taking up such wear will later appear. The lower 70 cylindrical member 5 extends between and is connected to the flywheels by means of the bolt 6 at a point below the center thereof and upon the vertical diameter, as viewed for instance in Fig. 2. This lower member 5 75 is mounted for pivotal or rocking movement with respect to the flywheel as the flywheel is rotated and is provided with curved seats or sockets 7 extending through the entire length thereof so as to accommodate the correspondingly formed lower edge portions 8 which are integral with the side wall members 9. These members 9 have turning movement with respect to the lower member 5 by virtue of the particular socket connection 80 just now referred to. The upper ends or edge portions of the members 9 are formed in the same manner and have like connections with correspondingly formed sockets provided in the intermediate floating members 10. The upper parts of the members 10 85 are likewise provided with the same form of sockets for connection or engagement with the correspondingly formed lower edge portions of the upper side wall members 11, 90 these upper side members 11 corresponding with the lower side members 9 and being substantial duplicates thereof. The upper edge or end portions of the upper side members 11 are formed in the same manner and 95 have like pivotal engagement in the correspondingly formed sockets provided in the lower side portion of the upper rocking cylindrical member 12. The member 12 has the marginal edge portion of each end there- 100 provided with a tenon 13 for engagement in the correspondingly formed groove pro-

vided in the inner side of the end portions of the bracket 14 which is supported and depends from the under side of the head 15. Thus the member 12 is rockably mounted on a fixed axis, while the member 5 is rockably mounted upon the rotating fly-wheel and eccentrically thereof. The bracket 14 is secured to the head 15 by means of screw bolts 16.

16 The side plates 9 and 11 as well as the intermediate connecting blocks 10 are spaced apart, as indicated in Fig. 2 of the drawing, so as to provide a chamber for the reception of gases which are admitted through the space 17 provided through the upper cylindrical member 12. The gases are admitted from the intake manifold 18, thence through the passage 19 to the port 20 by way of the valve 21. The operation of the intake valve 21 is controlled by the rocking lever 22 which is mounted upon the rock shaft 23, the stem of the valve being normally forced upwardly by means of the spring 24 which surrounds the same and bears up on the underside of 25 the disk 25 by the valve stem. The end of the lever 22 through which extends the valve stem is adapted to engage the nut 26 on the valve stem. The exploded gases are exhausted out through the port 27, thence past 30 the outlet valve 28, through the passage 29 to the exhaust 30. The valve 28 is controlled in its operation by a rock lever 31 which is mounted upon the shaft 23 in the same manner as shaft 22. The structure of the valve 35 28 and its other parts is the same as in the case of valve 21. The two rock levers 22 and 31 are controlled in their operations by means of the cams 32 and 33 which are mounted upon shaft 34 in proper timed relation so as to admit and exhaust the gases at the proper intervals. The shaft 34 which is mounted in suitable bearings on the casing is driven by pulley 35 which in turn is driven by the pulley 36 mounted upon the drive 40 shaft 1, there being a suitable belt or other connection between these two pulleys.

50 The spark plug 37 is mounted in the top of the casing and is so arranged that the gases will be exploded after they have been received in the distensible gas chamber and then placed under pressure by the collapsing action of the chamber in the manner already referred to. According to the arrangement here shown, which however might be modified within certain limitations according to the spirit of the present invention, the spark plug is screwed down in to a correspondingly threaded opening in the middle part of the bracket or block 14, as illustrated in Fig. 55 1. The spark plug is so positioned that the terminals of the same are properly located with respect to the space 17 into which the gases are received from the intake. The lead wire 38 provides a connection between the 60 single spark plug and the distributor box 39

which is of any suitable form so that there will be a spark for explosion of the gas for each revolution of the flywheel.

Briefly stated, the operation is as follows:

According to the present form of device, 70 the shaft 1 may be cranked by a suitable crank handle which is applied to the end 40 of the drive shaft so as to turn the flywheel from the position indicated in Fig. 2 through the dotted line position shown in the left 75 hand part of Fig. 2 and continued around to the point, at which the collapsible gas chamber has been filled by gases through the intake manifold and placed under compression by the collapsing action of the gas chamber, such position being illustrated by dotted lines in Fig. 2. The walls of the gas chamber in such position occupy substantially horizontal parallel arrangement or relation, as clearly indicated in this figure. During 80 approximately the first half of such cranking operation, the intake valve is open. With the gas under compression, the circuit is completed through the spark plug and there is an explosion of the compressed gas, with 85 the result that the gas chamber is expanded or distended and the flywheel is then continued in its rotation in clockwise direction under the power of the engine itself. This 90 firing period continues throughout substantially 90° and the force thereof is sufficient to carry the flywheel around to the same point where the next explosion takes place.

As soon as the one explosion has occurred, the walls of the gas chamber will be again 100 collapsed so as to come to occupy the position indicated in full lines in Fig. 2, during which time the gases are expelled out through the exhaust, the exhaust valve having been automatically opened at the proper 105 interval of time.

During such operation, the lower cylinder member 5 will rock on its pivoted end portions so as to occupy the several successive positions as the flywheel turns in its clockwise direction. Such action is made possible by virtue of the socket joint between the side walls of the gas chamber and the lower cylindrical member 5. Likewise the other connections between the side walls of the gas 115 chamber and the intermediate block 10 as well as the upper cylindrical member 12, make possible the distension and collapse of the walls in the gas chamber in the manner indicated in the several positions shown in 120 Fig. 2. During the distension and collapsing of the walls of the gas chamber, the upper cylindrical member 12 is rocked first in one direction and then in the other, throughout a complete angle of approximately 90°. 125 During the distension of the gas chamber, the upper cylindrical member is turned in a clockwise direction and upon explosion of the gases and consequent distension of the gas chamber under the engine's own power, 130

the upper cylindrical member is rocked or turned in a counterclockwise direction. At all times however, it will be seen that the passage 17 for the transmission of the gases through the upper cylindrical member is always in communication with the ports 20 and 27.

The outer surfaces of the side walls 9 and 11 are provided with vanes 9^a and 11^a as a means of facilitating the radiation of heat from these walls so as to keep down the temperature of the engine. Other suitable cooling means might also be adopted.

I have also provided a means of lubrication comprising the oil pump 41 which is mounted upon the top of the engine casing and which is adapted to be driven by the shaft 34 with suitable intermediate gear reduction. From the oil pump 41 there are provided suitable pipe connections 42 which connect with ducts or channels 43 provided through the upper part of the casing and which lead to the upper cylindrical member 12 for lubrication thereof. There is provided also the duct 44 through the cylindrical member 12, this duct opening at the point 45 for lubrication of the upper socket joint of the side plate 11 on the one side, while there is provided also another passage or port 46 through member 12 for the supply of oil to the corresponding joint of the other upper plate 11. Each of the upper cylindrical portions is provided with a port 47 extending therethrough and communicating with the vertically disposed channels or ducts 48 which lead to the upper surfaces of the lower cylinder portions of the plate members 11. Suitable ducts or ports are provided in these cylindrical portions, as indicated at 49, and they are adapted to communicate through the ports 50 with like ducts or ports 51 which extend through the upper portions of lower plate members 9. The lower ends of ducts or ports 5 have communication with channels 52 which extend downwardly and communicate at their lower ends with the ports 53 provided in the lower portions of side wall members 9. Ports 53 communicate with short ducts 54 which are provided in the lower cylindrical member 5 and which lead to the pivotal mounting of the same for lubrication thereof. The oil pump 41 is supplied from the reservoir 55 by means of pipe connection 56.

Any wear which might occur between the inner faces of the flywheel disks and the contacting portions during rotation of the same can be taken up by adjustment of the screws 4 which are adapted to force the inner parts 3^b inwardly. Suitable packing might also be provided between these parts so as to prevent leakage. Any other suitable means might also be adopted for this same general purpose.

Thus it will be seen that I have produced

an integral combustion engine in which there is but a single explosion for each revolution of the flywheel and in which the firing stroke is comparatively quick and of comparatively short duration, viz: only approximately 90°, and in which I have thereby cut down the amount of heat developed in the engine to a minimum, with a consequent increase in efficiency.

It will be seen also that in my present improved type of engine, the line of force along which the power of the explosion is exerted is substantially normal to the faces of the distending or collapsing walls of the gas chamber, with the result that the power is applied in a most direct manner and with the highest possible degree of efficiency. This is made possible by the particular rocking action of the upper cylinder member 12 and the accompanying movements of the other parts connected therewith. In this connection, it might be said that the collapsible gas chamber structure serves also as a connecting rod, since this is the only drive connection to the flywheel. Or in other words, the connecting rod might be said to be of collapsible, hollow form and serves as a gas chamber. Thus the gas chamber and connecting rod are comprised in a unitary or self-contained structure. And because of the particular structure and operation of this device, there is realized full advantage of the momentum of the moving parts without any appreciable intervals of inertia which are incident to certain other types of engines in which there is reciprocatory motion. In the present case, the parts are moving continuously and there is merely a progressive change in the direction of such movement. This means an increased efficiency.

Each of the periods of intake, compression, explosion and exhaust corresponds to approximately 90° or a quarter-turn of the fly-wheel; and for purposes of description and explanation, these four periods are here referred to as together constituting one complete cycle.

What I claim is:

1. An internal combustion engine, comprising a relatively fixed member, a movable member, means forming an expansible gas chamber arranged between and having operative connection with said fixed and movable members, said means including a flywheel upon which said movable member is mounted, and constituting part of the wall of said chamber, and means for exploding gases in said chamber so as to cause expansion of the same for operation of said movable member.

2. An internal combustion engine, comprising a relatively fixed member, a movable member, means forming an expansible gas chamber arranged between and having op-

- erative connection with said fixed and movable members, said means including a plurality of collapsible walls extending between said fixed and movable members and a fly-wheel upon which said movable member is mounted, and means for exploding gases in said chamber so as to cause expansion of the same for operation of said movable member.
3. An internal combustion engine, comprising a relatively fixed member, a movable member, means forming an expansible gas chamber arranged between and having operative connection with said fixed and movable members, said means comprising a plurality of collapsible walls extending between said fixed and movable members, and a sectional fly-wheel upon which the said movable member is mounted, the sections of said fly-wheel supplementing the said collapsible walls as an enclosure for the gas chamber, and means for exploding gases in said chamber so as to cause expansion of the same for operation of said movable member.
4. An internal combustion engine, comprising a relatively fixed member, a movable member, means forming an expansible gas chamber arranged between and having operative connection with said fixed and movable members, said means comprising a plurality of collapsible walls extending between said fixed and movable members, a two-part fly-wheel forming opposite walls of said gas chamber and supplementing said collapsible walls, said movable member being carried by said fly-wheel, and means for exploding gases in said chamber so as to cause expansion of the same for operation of said movable member.
5. An internal combustion engine, comprising a relatively fixed member, a movable member, means forming an expansible gas chamber arranged between and having operative connection with said fixed and movable members, said means including a fly-wheel upon which said movable member is mounted, means for taking up wear so as to prevent leakage of gas from said chamber, and means for exploding gases in said chamber so as to cause expansion of the same for operation of said movable member.
6. An internal combustion engine, comprising a relatively fixed member, a movable member, means forming an expansible gas chamber arranged between and having operative connection with said fixed and movable members, said means including a fly-wheel upon which said movable member is mounted, means for adjusting said fly-wheel so as to prevent leakage of gas from said chamber, and means for exploding gases in said chamber so as to cause expansion of the same for operation of said movable member.
7. An internal combustion engine, comprising a relatively fixed member, a movable member, means forming an expansible gas chamber arranged between and having operative connection with said fixed and movable members, said means including a sectional fly-wheel upon which said movable member is mounted, means for adjusting the sections of said fly-wheel so as to prevent leakage of gas from said chamber, and means for exploding gases in said chamber so as to cause explosion of the same for operation of said movable member.
8. An internal combustion engine, comprising a relatively fixed support, a member rockably mounted upon said support, a fly-wheel, a member rockably and eccentrically mounted upon said fly-wheel, a collapsible and distensible gas chamber being formed between said members, said chamber being adapted to be collapsed and distended by the force of gas explosions therein and said force being transmitted to said fly-wheel for operation thereof and means for exploding gases in said chamber.
9. In an internal combustion engine, a frame, a crank mounted for rotation therein, a pair of end members, rectangular pivotally connected wall members extending between said end members and forming therewith a chamber, two of said wall members being connected with said frame, two of said wall members being connected with said crank whereby rotation of said crank is accompanied by alternate distension and collapse of said chamber and means for effecting a power cycle in said chamber.
10. In an internal combustion engine, a frame, a crank mounted for rotation therein, a pair of fly wheels, rectangular pivotally connected wall members extending between said fly wheels and forming therewith a chamber, two of said wall members being connected with said frame, two of said wall members being connected with the said crank, whereby rotation of said crank is accompanied by alternate distension and collapse of said chamber and means for effecting a power cycle in said chamber.
11. In an internal combustion engine, a frame, pair of end members mounted for rotation therein, a crank secured between said end members, rectangular wall members extending between said end members and forming therewith a combustion chamber, two of said wall members being connected with said frame, two of said wall members being connected with said crank, and each of said wall members being connected with another wall member, whereby rotation of said crank is accomplished by alternate distension and collapsing of said chamber.
12. In an internal combustion engine, a frame, a pair of end members mounted for rotation therein, a crank extending between

said end members, rectangular wall members extending between said end members and forming therewith a combustion chamber, said chamber being in section a parallelogram, two of said wall members being connected with said frame, two of said wall members being connected with said crank, and each of said wall members being con-

nected with another wall member, whereby upon rotation of said crank said parallelogram is collapsed alternately upon each of its diagonals, and said chamber correspondingly extended and contracted. 10

In testimony whereof I hereby affix my signature.

JAMES S. REID.
